UNITED STATES PATENT OFFICE.

HERBERT MILTON COE, OF SAN JOSE, CALIFORNIA, ASSIGNOR OF ONE-HALF TO GEORGE W. DOBSON, OF SAN JOSE, CALIFORNIA.

SLEEPING-BALCONY.

1,212,019.

Specification of Letters Patent.

Patented Jan. 9, 1917.

Application filed November 9, 1915. Serial No. 60,525.

To all whom it may concern:

Be it known that I, HERBERT M. COE, a citizen of the United States, and a resident of San Jose, in the county of Santa Clara and State of California, have invented certain new and useful Improvements in Sleeping-Balconies, of which the following is a specification.

My invention relates to open air sleeping balconies, and the main object thereof is to provide a structure whereby said balcony may be roofed over in a thoroughly weatherproof manner and make the balcony a part of an adjacent room, or whereby the balcony may be rendered roofless and the adjacent room be rendered thoroughly weatherproof, thereby permitting use of the balcony in fair or inclement weather.

My invention is fully described in the following specification, of which the accompanying drawings form a part, in which like characters refer to like parts in each of the views, and in which:

Figure 1 is a sectional view of a portion 25 of the outer wall of a building having my balcony attached thereto, roofed over, as on the line 1—1 of Fig. 3; Fig. 2 is a similar view thereof unroofed, and with the adjacent room rendered weatherproof; Fig. 3 30 is a section taken on the line 3—3 of Fig. 1; Fig. 4 is an outside view of the balcony, with the wall of the building taken in section on the line 4—4 of Fig. 5; Fig. 5 is a sectional plan taken on the line 5—5 of Fig. 35 4; Fig. 6 is an enlarged fragment taken on the line 4—4 of Fig. 5, with the balcony roofed; Fig. 7 is a section taken on the line 7—7 of Fig. 6, but rear in the direction of the parts shown in Fig. 5; and Fig. 8 is 40 a modified form of a detail.

In the drawings forming a part of this application I have shown a portion 9 of the outer wall of a building having beams 10 extended therefrom upon which are 45 erected the walls 11, 12, and 13, of a balcony 14 open at its top and inner side and adapted for communication with a room 15 of the building.

As shown in Fig. 1 the balcony is provided 50 with a roof 16 and triangular side plates 17 and 18 adapted to operate as continuations of the balcony walls 11 and 13 and giving a desired pitch to the roof 16. The plates 17 and 18 are entirely free of the 55 balcony walls 11 and 13, but I form the joints

between the same in a weatherproof manner of any desired type, one of which is shown in Fig. 3, and the roof 16 and connected plates 17 and 18 may thus be moved from the balcony walls as a unit whenever desired.

In pivotal connection at 19 with each of the plates 17 and 18 is a bar 20 pivoted, at its lower end, at 21, to the respective balcony walls 11 and 13, the latter pivotal points being considerably nearer the building wall 9 than the pivotal points 19 are, whereby, when the roof is in position over the balcony, the bars 20 are arranged at a distinct upward and outward angle from the pivots 21 to the pivots 19 for a reason 70 later explained.

The inner side of the roof is provided with a stop 22 for limiting the outward movement thereof, and the outer side of said roof, at its inner end, is provided with a stop 23 adapted to bear against a hinged leaf 24 connected with the wall 9 to hold said leaf in place in a weatherproof manner, and said leaf may be sprung inwardly to the position thereof shown in Fig. 2, or it 80 may be of such height as to permit the passage of the forward or outer end of the roof and still be engaged by the stop 23 in the outward movement of the roof into balcony protecting position.

Secured to each side of the roof 16, at the inner end thereof, is a chain 25 of a predetermined length connected to a rope 26 provided with a large knot at the junction with the chain and passed through a stationary pulley 27, the other end of which rope is provided with a weight 28 movable in a box 29 in the wall 9.

In inclement weather the roof 16 is in the position shown for protecting the balcony, 95 but when it is desired to use the balcony as an open air sleeping place, the bed being assumed to be in place thereon, the occupant prepares for bed in the room 15, passes onto the balcony 14, grasps the handle 30, 100 and forces the roof 16 inwardly of the room 15. Inward movement of the roof causes the bars 20 to move toward vertical positions thus raising the outer end of the roof and permitting the inner end thereof to 105 move downwardly into the room 15 until said roof reaches the position shown in Fig. 2, resting upon the floor of the room 15, the plates 17 and 18 closing the sides of the opening through the wall 9 for the passage 110

of the roof. In this inward and downward movement of the roof the chains 25 are straightened out and strain applied to the ropes 26 to raise the weights 28, these 5 weights serving as a counter-balance for the weight of the roof, and it will be seen that the balcony is open at its top, whereas the room 15 is protected. In the morning, all 10 that is necessary is to grasp the handle 30 and raise the roof upwardly, this being aided by the weights 28, and outwardly because of the bars 20, until the stop 22 strikes against the balcony wall 12 and the stop 23 bears on the leaf 24, and both balcony and 15 room are protected from the elements.

My invention is very simple, though very practical and inexpensive, and may be adapted to different types of buildings and of different structures without departing 20 from the spirit of the invention, and I reserve the right to make all changes in and modifications of the structure shown and described which come within the scope of the appended claims. The form of hinged 25 bar connection shown in Fig. 8 is one such modification, the hinge being designated 31, but other forms might be conceived.

Having fully described my invention, what I claim as new, and desire to secure 30 by Letters Patent, is:—

1. The combination with a balcony opening directly to the interior of a building, of an inclined roof for said balcony provided with triangular side plates grooved 35 in their lower edges to receive the end walls of said balcony, and means for guiding said roof from said balcony into a position separating said balcony and interior.

2. The combination with a balcony opening directly to the interior of a building, 40 of a roof for said balcony and separable therefrom, said roof being adapted to be moved to separate said balcony and interior,

a bar pivoted to each end of said balcony and to each end of said roof for guiding 45 said roof in its movement, and a counter-weight for said roof when in said last named position.

3. The combination with a balcony opening directly to the interior of a building, 50 of an inclined roof for said balcony provided with triangular plates rigidly secured to said roof, said plates resting on the end walls of said balcony, the under edges of said plates forming tracks on which said roof is carried from said balcony into a 55 position separating said balcony and interior.

4. The combination with a balcony opening directly to the interior of a building, 60 of a roof for said balcony and separable therefrom provided with plates secured to said roof, and rollers carried by the inner upper corners of the end walls of said balcony for anti-frictionally supporting said roof plates 65 in the roof movement from said balcony to said interior.

5. The combination with a balcony opening directly to the interior of a building, 70 of a roof for said building and separable therefrom, two bars placed one at each end of said balcony and pivoted at the lower ends to the respective end walls of said balcony and at their upper ends to the respective 75 ends of said roof, and a truss rod rigidly connected with the said bars to insure complementary movement thereof in the roof movement out of and into balcony protecting position.

In testimony whereof I have signed my 80 name to this specification in the presence of two subscribing witnesses.

HERBERT MILTON COE.
